UNITED STATES PATENT OFFICE

144,058

DESIGN FOR AN AIRPLANE

Alexander Kartveli, Huntington Station, and Murray Berkow, Flushing Heights, N. Y., assignors to Republic Aviation Corporation, a corporation of Delaware

Application February 24, 1944, Serial No. 112,698

Term of patent 14 years

(Cl. D71—1)

To all whom it may concern:

Be it known that Alexander Kartveli and Murray Berkow, citizens of the United States, and respectively residents of Huntington Station, Long Island, New York, and Flushing Heights, New York city, New York, have invented a certain new, original, and ornamental Design for an Airplane, as described in the following specifications and shown in the accompanying drawings, wherein:

Fig. 1 is a perspective view of an airplane embodying the present design with the landing gear protracted;

Fig. 2 is a top plan view thereof;

Fig. 3 is a front view thereof with the landing gear retracted; and

Fig. 4 is a side elevation thereof with the landing gear retracted.

What is claimed is:

The ornamental design for an airplane, substantially as shown.

ALEXANDER KARTVELI.
MURRAY BERKOW.
